United States Patent Office

Des. 195,497

Patented June 25, 1963

195,497

SLIPPER

Florence B. Zacks, Columbus, Ohio, assignor to R. G. Barry Corporation, Columbus, Ohio, a corporation of Ohio

Filed July 9, 1962, Ser. No. 70,843

Term of patent 14 years

(Cl. D7—7)

I claim:

The ornamental design for a slipper, as shown and described.
